ELECTRIC STOVE

Abe O. Samuels, Rochester, N. Y., assignor to
Samson-United Corporation, Rochester, N. Y.

Application February 19, 1935, Serial No. 7,238

10 Claims. (Cl. 219—37)

This invention relates to electric stoves and has for its object to provide such a stove with a louvred grid which permits direct heat radiation from the heating unit but prevents metal objects generally used around the stove from coming into contact with any portion of the heating coil of the heating unit.

A further object of this invention is to increase the strength of the stove frame by forming the grid integral therewith.

Another object of this invention is to provide a novel form of suspension for the heating unit of the stove.

All these and other objects of this invention will become more readily apparent from the detailed description thereof which follows, reference being had to the accompanying drawing in which

Figure 1 is a top plan view of the electric stove.

Figure 2 is a vertical sectional view of the stove, 20 the section being taken on the line 2—2 of Figure 1.

In the figures like reference numerals indicate like parts.

In electric stoves in which the heating coil of the heating unit is located in suitable grooves provided in a base of refractory material and the heating coil is thus exposed so that any metallic implement can be brought in contact therewith and accidentally provide a short circuit between it and the stove frame, the requirement of the Board of Underwriters makes it necessary to provide such a stove with a two-pole switch so that the heating unit is completely cut out of the electric circuit whenever the switch is opened. In my present invention this requirement has been eliminated by the use of a grid provided with louvers which cover the heating unit and prevent the insertion of any implement used around the stove to make contact with the heating coil. These louvers are arranged so that they do not obstruct the radiation of heat from the heating unit and thus will not affect the efficiency of the stove. The use of a single pole switch is therefore now permissible with this type of heating unit and makes it possible to simplify the construction of the stove and reduce the cost of manufacture thereof.

As illustrated in the figures of the drawing, the electric stove comprises a metal casing 1 which is supported on suitable legs 2, 2. The casing is open at the bottom and closed on all sides and the top and in the closed top is struck up a grid which, in the present instance, comprises a slightly elevated circular platform 3 bordered by a concentric supporting ridge 4 and provided with a

central supporting member 5 and suitable supporting ribs 5A, 5A which extend radially from the central supporting member within the concentric supporting ridge 4. The ribs 5A or other suitable structure of platform 3 provide for expansion and contraction of platform 3.

The supporting members thus provided by the grid, together with the platform 3, are struck up from the underside of the top of the casing and form an integral part thereof. The segmental sections of the platform 3 between the elevated supporting members of the grid have the angularly projecting louvers 6, 6 struck up therefrom. In the form illustrated in Figure 1, these louvers are concentric to the grid and incline upwardly toward the center thereof and are so arranged that their outlet openings between the upper edge of one louver and the lower edge of the succeeding louver are restricted and are located in a substantially vertical plane so that no object used around the stove can be conveniently inserted or dropped therethru. Thus as shown particularly in Fig. 2, the louvers may be formed as oblique bar members positioned so that the upper edge of one bar is substantially in register with the lower edge of an adjacent bar.

The heating unit 7 is made up of a suitable refractory material and is provided with open grooves 8 into which is nested the heating coil 9. The heating unit is fastened to the underside of the grid and its louvers by means of a pair of clamping screws 10 and 11 and the cover 12. This cover is channel shaped and extends across the bottom of the heating unit with its outwardly flaring flanges 13 and 14 resting against the bottom of the heating unit. The clamping screws project thru the grid, the edges of the heating unit and thru the flanges 13 and 14 of the cover to have the clamping nuts 15 which are threaded onto the bolts, simultaneously clamp the cover 12 against the bottom of the heating unit and the heating unit against the bottom of the grid and its louvers.

The cover 12 thus forms a shield against the direct radiation of heat from the bottom of the heating unit and provides an air chamber which extends along the bottom of the heating unit from which the heat radiated from the bottom of the heating unit, can escape thru the openings 16, 16 in the sides of the cover. The heat from the bottom of the heating unit is thus laterally distributed in the casing so that part of it can escape thru the openings 17 provided in the top of the casing on the outside of the grid. In this way excess heat from the heating unit is dissipated.

pated and is not radiated against the table top or other supporting surface on which the stove is supported.

From an inspection of Figure 2 of the drawing, it will be apparent that the louvers 6, 6 overhang the groove 8 and the heating coil 9 located therein so that this heating coil is fully protected and no metal object or implement dropped onto the grid of the stove can enter the groove and cause 10 a short circuit between the heating coil and the casing of the stove. The switch 18, located at one end of the air chamber, provided by the cover 12, can therefore be a single pole switch for the control of the electric current as the danger of causing a short circuit between the heating coil and the stove casing has been eliminated by the use of the covered grid over the heating unit, as pointed out above.

I claim:

20 1. In an electric stove the combination of a metal top, a grid formed integral in said top, louvers struck up from said grid, a heating unit, a cover for the bottom of said heating unit and clamping means for clamping said cover against 25 said heating unit and said heating unit against the under side of said grid.

2. In an electric stove the combination of a stove top, a grid provided in said stove top, louvers in said grid to provide lateral openings 30 therein, a heating unit fastened to the under side of said stove top, a substantially U shaped cover on the under side of said heating unit having openings in the side thereof and providing a shield for the bottom of said heating unit with 35 an air chamber between it and said shield.

3. In an electric stove the combination of a grid having a substantially circular supporting ridge, radially arranged supporting ridges within said circular ridge dividing said grid into segmental sections, angularly disposed and concentrically arranged louvers struck up in said segmental sections of said grid and inclined toward the center of said grid.

4. In an electric stove the combination of a 45 casing closed on all sides and the top and open at the bottom, an electric heating unit comprising a plate member of refractory material with a heating coil embedded therein, a hollow cover, and clamping means for clamping said hollow 50 cover against the bottom of said plate member and said plate member against the under side of the top of said casing.

5. In an electric stove as set forth in claim 4 in which the top of the casing is provided with 55 louvered openings above the heating unit.

6. In an electric stove the combination of a sheet metal top, a sheet metal casing surrounding said sheet metal top, a heating unit mounted within said casing below said sheet metal top, circularly arranged louvers inclined toward a common center provided in said sheet metal top and expansion means provided in said sheet metal top and dividing said louvers into segments so as to provide lateral expansion between the louvered sections of the sheet metal top.

7. In an electric stove the combination of a sheet metal casing, a sheet metal top for said casing, a grid raised on said sheet metal top, concentrically arranged louvers inclined toward a common center provided in said grid, a heating unit clamped to the under side of said grid and a cover clamped to the bottom of said heating unit within said casing to provide an insulating chamber between said heating unit and the table top on which the electric stove is supported.

8. In an electric stove, a grid having a substantially circular supporting ridge and being provided with substantially radially arranged means dividing said grid into sectors and adapted to permit expansion and contraction of said grid, an electric heating unit supported on the under side of said grid and adapted to radiate heat upon said grid, and a plurality of relatively long arcuate louvers provided in said sectors of said grid and inclined toward the center of said grid.

9. In an electric stove, a metal top, a grid provided in said metal top and having a substantially circular supporting ridge and being provided with substantially radially arranged means dividing said grid into sectors and adapted to permit expansion and contraction of said grid, an electric heating unit supported on the under side of said grid and adapted to radiate heat upon said grid, said grid being provided in said sectors with a plurality of substantially parallel bar members positioned obliquely of said grid and with the upper edge of one bar substantially in register with the lower edge of an adjacent bar.

10. In an electric stove, a plate comprising a grid area bounded by a ridge of substantially circular contour, said grid area being provided with substantially radially disposed supporting ridges dividing said grid area into sectors, a plurality of arcuate louvers formed in said sectors and being substantially parallel with said circular boundary ridge, and an electrical heating unit supported on the under side of said grid area and adapted to radiate heat upon said grid area.
